GLOVE OR SIMILAR ARTICLE

Richard C. Zuckerwar, Gloversville, N. Y.

Application October 30, 1956, Serial No. 43,586

Term of patent 3½ years

(Cl. D3—11)

Fig. 1 is a palm side view of a glove or similar article, showing my new design.

Fig. 2 is a view of the opposite side of the glove shown in Fig. 1.

The dominant feature of my design resides in the stitching as shown on the palm portion of the glove.

I claim:

The ornamental design for a glove or similar article, substantially as shown and described.
